(57) **CLAIM**

We claim the ornamental design for a lithium ion battery module, as shown and described.

DESCRIPTION

FIG. 1 is a front perspective view of an ornamental design for the lithium ion battery module;

FIG. 2 is a front view of the lithium ion battery module of FIG. 1;

FIG. 3 is a rear view of the lithium ion battery module of FIG. 1;

FIG. 4 is a right side view of the lithium ion battery module of FIG. 1;

FIG. 5 is a left side view of the lithium ion battery module of FIG. 1;

FIG. 6 is a top view of the lithium ion battery module of FIG. 1;

FIG. 7 is a bottom view of the lithium ion battery module of FIG. 1; and,

FIG. 8 is a rear perspective view of the lithium ion battery module of FIG. 1.

The broken lines in the FIG. 5 view, the FIG. 7 view, and the FIG. 8 view depict environmental subject matter that forms no part of the claimed design.
